CONTAINER CLOSING METHOD AND APPARATUS

Joseph C. Lang, Pittsburgh, Pa., assignor to Bocjl Corporation, Pittsburgh, Pa., a corporation of Delaware

Application March 3, 1944, Serial No. 524,849

13 Claims. (Cl. 93—42)

1

This invention pertains to the art of closing containers, particularly rigid containers, such as cardboard boxes or boxes made of corrugated fiber board or the like.

The invention is particularly useful for closing corrugated containers and will be specifically described in this connection, but the invention is applicable to the closing of containers made of other materials, particularly rigid or semi-rigid containers of a fibrous nature as distinguished from containers such as paper bags and the like, which are not of a rigid or semi-rigid character. While this invention is primarily designed for the closing of box tops, and will be so described, it is also applicable to the securing or closing of the bottom or of a side corner of a box or carton, and the invention is intended to include and cover any such use.

Cartons or containers to which the present invention is applicable are widely used for the shipment of all sorts of commodities. While no difficulty is encountered in closing the bottom of such receptacles, ordinary stapling methods being acceptable, there is a problem in sealing or closing the tops of these containers and holding them closed. While the use of staples is highly desirable, conventional methods of stapling as heretofore employed cannot be used, because there is no satisfactory way, on account of the difficulty of providing an anvil to turn or clinch the inner ends of the staple legs. In other words, if a staple is driven into the top flaps of a box into the underlying flaps, difficulty is encountered in clinching the staple. If the contents of the box are such as to permit the flaps to sag or bow downwardly when stapling pressure is applied, still further difficulty is encountered. While various methods have been devised by me and by others for overcoming this difficulty, there are still various situations where the box cannot be satisfactorily stapled. In some cases, it is considered desirable, in order to use staples, to have a thin anvil which can be inserted under the cover flaps of the box and withdrawn after the stapling has been completed. This of course leaves an opening where the anvil has been withdrawn, and also difficulty is encountered due to the fact that an anvil thin enough to be so used is apt to have too much flexibility, particularly in the larger sizes.

Consequently cartons are commonly closed, either by pasting or by using gummed tape, both of which methods of fastening are likely to result in the carton coming open if it is stored in a damp place. Moreover, such cartons may be pilfered by thieves who moisten the tape, remove the con-

2

tents from the carton, and then apply a fresh strip of tape to conceal from detection the loss of the contents of the box.

The present invention provides a method and apparatus for using an inserted or driven fastening means such, for example, as a staple, in such manner as to avoid the difficulties heretofore encountered. More particularly, according to the present invention the box, after being closed, is pinched along the corners formed between the top and the end walls of the container, and a fastener is inserted, this fastener in effect passing diagonally through the corner of the container. In the case of a staple, the bridge or head of the staple will then be at the top of the box while the ends of the legs of the staple will pass diagonally through the box and be clinched in the end walls of the box. With this construction the box is very safely closed, and the cover flaps are held shut, and it is not possible to open the top of the box to secure access to the contents thereof without mutilating the box. The box will be fastened securely enough in this way to meet shipping requirements for containers of this kind, and the difficulties heretofore attendant in the use of staples for closing box tops is eliminated.

While the invention is specifically illustrated in the accompanying drawings for the closing of cartons by the use of what is known as a stitcher, i. e., a machine which forms staples from a continuous like wire and drives the staples that are so formed, it is applicable to the closing of boxes by stapling, using preformed staples, or by the use of other fasteners passing diagonally through the corner of the container.

My invention may be more fully understood by reference to the accompanying drawings, in which:

- 40 Fig. 1 is a perspective view of a typical box or carton before being closed and fastened;
- 45 Fig. 2 is a perspective view of the box after staples have been put therein;
- 50 Fig. 3 is a fragmentary section on larger scale through a corner of the box in the plane of line III—III of Fig. 2;
- 55 Fig. 4 is a similar section in the plane of line IV—IV, of Fig. 2;
- 58 Fig. 5 is a more or less schematic side elevation of a machine embodying my invention, only the outline of the parts being indicated;
- 62 Fig. 6 is a fragmentary view of the stapling head of the machine shown in Fig. 5 with the stapling head, however, being turned to a vertical position, the view showing the parts in the

position which they assume before the driving stroke begins;

Fig. 7 is a similar view showing the position of the parts at the end of the driving stroke;

Fig. 8 is a fragmentary sectional view on a larger scale showing the two gripping jaws apart from the remainder of the machine, the view being taken on the center line of the jaws;

Fig. 9 is a front elevation of the apparatus shown in Fig. 6;

Fig. 10 is a front elevation of the guide plate indicating in dotted lines in Fig. 9;

Fig. 11 is a perspective view of the upper gripping jaw;

Fig. 12 is a perspective view of the lower gripping jaw;

Fig. 13 shows the jaw operating cam in elevation;

Fig. 14 is a perspective view of the jaw operating cam;

Fig. 15 is a detail view showing a bracket structure of the lower end of the stapling guide;

Fig. 16 is a side elevation of the part shown in Fig. 15;

Fig. 17 is a view similar to Fig. 5 of a slightly modified form of apparatus;

Fig. 18 is a view partly in section and partly in side elevation of a portion of the machine shown in Fig. 17 indicating the manner of engaging the container at the moment of driving the staple;

Fig. 19 is a view similar to Fig. 18 showing the position of the parts at the beginning of the operating cycle; and

Fig. 20 is a front elevation of the apparatus shown in Figs. 18 and 19.

For the purpose of explaining the method contemplated herein, reference may first be made to Figs. 1 to 4, inclusive. A conventional box usually has two side walls, designated A, and two end walls designated B. The end walls are provided at their top with inwardly turned flaps b, and the side walls A are provided along the upper edge with flaps a. In closing the box, the flaps b are first folded in and then the flaps a are folded over. The flaps a preferably overlap.

After the box is closed, the end corners are pinched or gathered by means of gripping jaws, and while they are held in this condition, a fastening means such as a staple is driven through the part that is gathered up in this way. The staple or other fastener enters one of the top flaps, passes diagonally across the corner of the container, emerges at the sides of the container, and the ends are clinched where they emerge.

When the box has been stapled across the ends, the flaps will be securely held down, and the box effectually sealed. The condition of the fastening may clearly be seen by reference to Figs. 3 and 4. The two figures are very similar, except that where the two top flaps a overlap their end, four thicknesses of paper or cardboard are penetrated by the staple whereas, as shown in Fig. 3 at each side of the overlapping area, the staple passes through only three thicknesses of paper.

In Figs. 3 and 4 the fastening means, illustrated as comprising a staple, is designated S. These staples serve to hold the container in the bunched or gathered form to which the corner is squeezed prior to the penetration of the staple, forming a reinforcement along the edge of the box and serving to strengthen the box. Sometimes it may be desirable to provide this folded or gathered condition along the side edges of the box as

well as across the corners, and this is illustrated by the staples S' in Fig. 2.

Generally speaking, therefore, the novel method in the present invention comprises the pinching or squeezing of the corner of a rigid or semi-rigid container to bring the corner portion where the flaps and end walls meet into a gather or fold, and passing a fastener through the portion thus pinched or folded together to permanently hold it in this condition. Instead of the conventional staple, the invention in its broadest aspects contemplates the use of any other suitable fastening means, including the stitching of the fold or gather across the diagonal of the corner by a sewing or stitching machine using thread, string, or flexible wire, and while staples have been specifically illustrated, it is to be understood that such other forms of fastening are included within the contemplation of this invention.

In practicing the invention, the fastening is accomplished by a stapling means or other fastener driving means positioned diagonally with respect to the sides and top of the box. This may be accomplished either by keeping the box horizontal and throwing the stapling head at an angle of about 45°, as shown in Fig. 5, or by having the stapling head vertical and tilting the box to an angle of about 45°, as is shown in Fig. 17. It is contemplated that the staple driving mechanism of the form shown in Fig. 5 can be in the position illustrated in Fig. 5 or in the position illustrated in Fig. 17 and likewise the mechanism shown in Figs. 17, 18 and 19 can be put on an incline as indicated in Fig. 5.

The driving of the staples in the manner described is conveniently accomplished on a machine of the general type schematically shown in Fig. 5 and more fully shown in Figs. 6 to 16.

In Fig. 5 the mechanism for forming and driving the fasteners is positioned at a 45° angle so as to operate across the corner of the box, but this mechanism may, as an alternative arrangement be vertical, as indicated in Fig. 17, with the box held at a 45° angle. All of the detail views, Figs. 6 to 16 are, for clearness of illustration, arranged as if the driver were vertical.

Referring now to Fig. 5, the machine has a base 2, a pedestal 3, a vertically adjustable work holding table 4 to receive the box C. At the top of the pedestal is a driving motor 6 which operates, through gearing 7, the stitcher, i. e., staple forming and driving mechanism—indicated generally as a driving head 8, this stitcher receiving wire W from a spool W'.

The stitcher or stapling head 8 forms and drives a staple in a manner well known to those skilled in the art, and insofar as the forming and driving mechanisms are concerned, they per se constitute no part of the present invention and the parts are shown only insofar as they are required for the explanation of the novel features of my invention. This stapling head includes a grooved cam 10 which is rotated by the motor. The cam also carries an eccentric pin 11 to which is attached a connecting link 11a.

A cam follower or roller 12 in the groove 10a of the cam 10 is carried on a reciprocable forming mechanism 13. This mechanism in its downward movement will cut off a length of wire which has previously been fed by feed rollers 14 into the head 8, and then bend the two end portions of the piece which is cut off downwardly to form a conventional U-shaped staple, as is well known in the art.

The connecting link 11a is connected at its lower end with a reciprocable driver 15 that is relatively movable in the forming mechanism 13. Fig. 9 shows the position of the parts when both the driver and former are in the position they assume at the moment when the cycle of forming and driving is about to begin, that is, the parts have been raised to the starting or uppermost part of the stroke.

Assuming the parts to be in the position shown in Fig. 9, and the cam to be revolved in a counter-clockwise direction, the cam follower 12 and former 13 will be forced down rapidly while the driver, operating under the action of the eccentric pin, will move down much more slowly. The former will complete the cutting of the wire, and the making of a staple, and then will dwell on portion 10b of the groove 10a of the cam while the driver 15, which has a longer stroke, will continue to move down, contacting the staple that has been formed and forcing it from the end of the guide.

The completion of the driving stroke will occur when the eccentric pin 11 is 180° from the position shown in Fig. 9. At that time, the cam follower 12 will be at the end of the dwell portion 10b of the cam groove 10a and both the driver and the staple former will move upwardly to the starting position. As before stated, so much of the apparatus pertaining to the forming and driving of the staples as has been described is conventional and forms no part of the present invention per se.

The present invention contemplates the gripping or pinching of the corner portion of the box or container to hold it while the staple is being driven diagonally therethrough, with the lower gripping jaw constituting also an anvil against which the legs of the staple are projected, and by means of which they are turned. Accordingly, a bracket 16 is secured to the rear face of the stapling head. Carried on this bracket is a pivot pin or shaft 17. The bracket 16 is shown detached from the machine in Fig. 16. The opening 18 at the forward end of the horizontal arm of the bracket receives the shaft 17. As shown in Fig. 15, the forwardly projecting arm of the bracket 16 is bifurcated, providing a space 19 directly under the stapling guide.

Mounted on the shaft 17 is a lower box engaging jaw or gripper, designated generally as 20, which is best shown in Fig. 12. It has a hole 21 through which the shaft 17 passes. It has a narrow portion 22 forwardly of this hole which operates in the space 19 in the bifurcated horizontal portion of the bracket 16. It has forwardly of the portion 22, a cross arm 23 and at the center of the cross arm 23 are two transversely extending concaved anvil portions 24. These anvil portions are so positioned that the ends of the legs of the staple being projected from the end of the stapling guide will, after passing through the box, strike these surfaces to be turned back into the box to clinch the staple.

Extending rearwardly from the opening 21 the lower jaw member 20 has an arm portion 25 in which is a cam engaging recess 26. By reason of its mounting on the shaft 17, the jaw member can move in a limited vertical arc.

Cooperating with the lower jaw member is an upper jaw member shown in detail in Fig. 11 and designated generally as 27. The upper jaw member is in the form of a frame having an opening therethrough, it having side arms 28, a rear cross arm 29, a forward cross arm 30, and downwardly

projecting lug portions 31 adjacent each end of the forward cross arm 30. These lug portions each having an opening 32 therein through which the shaft 17 passes to provide a pivotal support for the jaw. Projecting forwardly from the cross arm 30 are two spaced box engaging jaw portions 33. The space between the two jaws 33 is substantially equal to the width of the portion 22 of the lower jaw member. The side arms 28 are recessed on their lower faces as indicated at 34 to provide cam engaging surfaces.

The two jaw members fit together as best shown in Fig. 8, in which the box gripping portions are open to the full limit of their movement. Secured to the bracket 16 are keepers 35 (see Fig. 16) providing bearings for portions 37 of a cam shaft, this cam shaft having flattened cams or lobes 38 thereon. The cam is best shown in Figs. 13 and 14. The two end lobes 38 engage the surfaces 34 on the side arms of the upper jaw member and the intermediate lobe 38 engages the cam surface 26 on the lower jaw member. This engagement is indicated in Fig. 8. When the cam shaft is rotated from the position shown in Fig. 8, the lobes, instead of being flatwise with reference to the jaws are then edgewise, or more nearly so, thereby operating the jaws to force the forward box engaging portions 23 and 33 respectively toward each other from the position shown in Fig. 30 to the position shown in Fig. 7. As also shown in Fig. 8, the rear portions of the two jaws may be linked together by a tension spring 39 which yieldably acts in opposition to the cam for opening the jaws when the cam is turned back to the flatwise position.

The present invention contemplates the operation of the cam from the operation of the stapling mechanism, and in proper sequence with respect thereto, so that when the corner of a box is thrust in between the open jaws before the start of the stapling cycle, the corner of the box will be pinched or gathered together between the cross head 23 and the lugs 33, and firmly held while the staple is thrust through the layers of paper 45 of box board thus pinched together. The jaws should then release the box after the staple has been driven. For operating the jaws in this manner, an arm 40, best shown in Fig. 6, is loosely mounted on the shaft 17 so as to turn on the shaft without necessarily turning the shaft itself. This arm extends rearwardly and intermediate its ends it is provided with a pin 41 which projects laterally from the face thereof. At its outer end it is provided with a slot 42. Fixed on the end portion 37a of the cam shaft is a crank arm 43, the crank being faced on the cam shaft 37 so as to transmit motion to the shaft. The outer end of the crank arm 43 carries a pin 44 that passes through the slot 42.

As best shown in Fig. 9, the stapling head has two spacing sleeves 45 projecting from one side thereof. These spacing sleeves are secured in place by bolts 46 that pass through slots 47 in a slide plate 48 which plate is retained for sliding movement against the spacing studs 45 by the heads of the bolts 46, there being spacers 49 to prevent the bolts from binding against the plate 48. The slots 47 provide clearance to permit the plate 48 to move up and down, but the plate is restrained from movement in any direction other than vertical rectilinear movement. The plate has a downwardly and rearwardly extending projection 48a, in the lower terminal of which is a transverse slot 50 (see Figs. 6 and 7) and the pin 75 41 on the lever arm 40 passes through this slot.

The arrangement is, therefore, such that when the plate 48 moves up and down it transmits a rocking movement to the arm 40, swinging the arm 40 in an arc. The pin 44 on the crank arm 43 transmits this movement through the crank arm to the cam shaft 31 to turn the cam shaft through the required arc. The linkage which has been described for operating the cam shaft constitutes a system of toggle levers for converting the rectilinear movement of the plate 48 to a rotary movement of the cam. The slots 42 and 50 allow for the relative difference in arcuate movement of the various parts.

For operating the plate 48, the motion of the staple forming mechanism 13 is utilized because the staple forming mechanism operates, as above explained, in advance of the driver so as to complete its stroke before the driver has moved down to staple driving position, and because the staple forming mechanism has a period of dwell while the staple is being driven and set. This motion may advantageously be used for the operation of the jaws which must close and squeeze the box together before the driving of the staple starts, and which must, during the dwell of the staple forming mechanism, continue to pinch the box while the staple is being driven therethrough.

For transmitting motion from the staple forming mechanism as described, there is secured to the upper end of the part 13 (see Fig. 9) a rigid arm 51 having a terminal portion 52 that passes through a short slot 53 in the plate 48. Projecting from the terminal portion 52 is a pin 54. A pin 55 on the plate 48 is positioned directly above the pin 54 and a tension spring 56 connects the two pins.

With this arrangement, when the mechanism 13 starts to move down, the arm 51 will, of course, move down and motion will be transmitted first through the spring 56 to the plate 48 to move the plate down and initiate the closing movement of the jaws. As the closing movement of the jaws encounters resistance in pinching the box together, strain will be put on the tension spring 56 so that it will stretch to a point where the terminal portion 52 will be at the lower limit of the slot 53, and further downward movement will be transmitted directly from the bracket 51 to the plate 48. At the instant of stapling, there will be additional pressure on the lower jaw member, and it is desirable that the lower jaw member should move down very slightly to let the staple penetrate the paper, and then be turned back in. This motion is permitted by reason of the slot 53, because at this time the plate 48 can move down with respect to the bracket 51, relieving slightly the tension on the spring 56. The lost motion thus provided, however, is quite slight because of the short length of the slot 53. This arrangement also compensates for variation in box wall thickness.

Upon completion of the driving of the staple, the former 13 will start to move up, taking with it the bracket 51. An upward movement to the plate 48 is thus effected, rotating the cam shaft in the reverse direction, thereby permitting the jaws to open and release the box.

To enable the box to be rapidly and effectively engaged by the jaws, my invention further contemplates the provision of a guide structure on the stapling head, which will direct the corner of the box into the bight of the jaws. This guide structure comprises two wings or plates 57 and 58 (see Fig. 10), secured together by angle members 59. The two plates are cut away as best

shown in Fig. 10, to fit around and provide clearance for the end of the staple guide and the jaws. The two plates are joined at an angle of 90° because of the corner of the box forming an angle of 90° and they are supported so that each plate forms an angle of 45° with a plane passing horizontally midway between the two jaws as viewed in Figs. 6 and 7. When the jaws are opening as shown in Fig. 6, they are retracted through the opening at the center of the guide structure so as to be entirely back of the surfaces of the two guide plates. As the jaws swing together, they project, as shown in Fig. 7, into the space between the two guide plates. With this arrangement, the box is set into the machine when the jaws are open, until the two surfaces adjacent the corner to be stapled contact the plates 57 and 58, and the corner of the box is as close to the corner where the two plates intersect as possible. With the box held in this location, the machine is then operated to pinch and staple it in the manner described.

The guide structure comprising the two plates is rigidly and firmly held in position by arms or brackets 60 secured to the back of the upper plate 58. The ends of these arms are bolted to the side faces of the stapling head. As shown in Figs. 6 and 7, the ends of the brackets may be slotted so that the securing bolts 61 may be loosened to permit the guide to be adjusted and tightened when the guide has been set in the proper position.

Where the stapling head is at an angle of 45°, as shown in Fig. 5, the upper plate 57 extends horizontally and the lower plate 58 is vertical. The work holding table 4 may be provided with a plate 62, or bed member on which the box, normally rests, which plate can be elevated by any appropriate means. I have shown a rod 63 connected to the bottom of the plate 62 and passing through the bed of the work holding table. The lever 64, pivotally supported at 65, provides a means for elevating the box into the bight of the jaws.

In operation the box is set on the plate 62 with the end wall adjacent the back wall 4a at the table. The operator then presses down on the outer end of the lever 64 to thereby raise the box, and when the box is in position, steps on the treadle 66 to operate the machine. Upon the position where the next staple is to be driven and again raised and stapled. It is of course contemplated that the raising of the box may be automatically accomplished, or that other means than that shown may be used, but this specific means forms no special part of the present invention.

As best shown in Figs. 15 and 16 the forwardly extending portion of the bracket 16 carries a stop member 16' that extends across the top of the upper portion of the bifurcation and which is held in place by rearwardly extending portions 16a, secured to member 16 by bolts 16b. This stop engages the corner of the box immediately back of the point of stapling and assures that the successive staples will be in line.

In the embodiment of the invention as described, the pinching of the box is accomplished by means of jaws that operate from the staple forming mechanism. It is, however, contemplated that the gripping or pinching of the corner of the box be accomplished directly from the motion of the driver, and one way of effecting this result is illustrated in Figs. 17 to 20 inclusive.

In this modification, the base of the machine is designated 70, and 71 is the column, at the top of which is the stapling head 72, the motor 73, and gearing 74 for operating the stapling mechanism. The work table is designated 75, and it is provided with a holder 76 which holds the box at an angle of 45°.

Secured to the lower end of the stapling head is a bracket 77, at the forward end of which is a pivot pin 78 that supports a jaw member designated generally as 79, and which has a forwardly extending jaw portion 80 with anvil surfaces 81 therein. The jaw member 79 has a rearwardly extending tail portion 82 and it has an upwardly extending lug or arm 83 on which is a roller 84. At the lower end of the driver is a tapered cam surface 85 which cooperates with the roller while a compression spring 86 under the tail 82 exerts an upward pressure against the tail, tending to move the jaw 80 to the open position shown in Fig. 19. The driver, designated 87, in addition to having the surface 85 hereinbefore mentioned, also has an inclined surface 88 in which are formed a series of teeth.

In operation, the box is set in the position shown in Fig. 17. As the driver comes down to drive the staple, the inclined surface 85 bearing against the roller 84, cams the roller rearwardly, rocking the jaw member against the compression of the spring 86, tending to pinch the box between the roughened surface 88 and the jaw 80, the box being pinched in the manner shown in Fig. 18. As the pinching is occurring, the driving of the staple is also taking place, so that the box is gathered together at the end, and stapled with the staple passing diagonally through the corner in the manner hereinbefore described. The arrangement shown in Figs. 18 to 20 inclusive is less effective than the arrangements previously described, where a stitching machine is employed, but this arrangement can be satisfactorily used, especially on a slower operating machine, and one wherein preformed staples are used.

While I have illustrated and described certain specific embodiments of my invention, and methods of effecting it, it will be understood that other modifications are also within the contemplation of my invention, and under the scope of the following claims.

I claim:

1. The method of closing a carton which comprises pinching together a corner between two intersecting initially disconnected perpendicular surfaces thereof together into parallelism and passing fastening means therethrough.

2. In the closing of a carton, the steps which comprise squeezing together into parallelism the corner where the detached edge of a lift and a wall surface intersect and then entering fastening means into one surface and having it emerge on the other.

3. The method of closing a carton having a cover flap with a free edge perpendicular and adjacent to one of the walls of the carton which comprises pinching the said edge and wall at the corner where they intersect until they are in parallelism and then passing fastening means through the corner while it is so pinched together.

4. The method of securing together perpendicular walls of a carton which comprises driving a fastener diagonally across the corner formed by the intersection of the free edges of two walls, and pinching the corner together to bring the

corner portions through which the fastening means is passed into parallelism while the fastening means is being driven.

5. Carton sealing means comprising a carton holding support and means positioned to cooperate with a carton on the support for passing a fastening means diagonally across a corner of the carton, and means for squeezing together the corner portions of the carton through which the fastener is entered during the passing of the fastening therethrough.

6. Carton sealing means comprising means for pinching into parallelism the wall portions at the corner formed by two intersecting walls of a carton, other means for passing a fastening means through said corner while it is so pinched and means for supporting the carton in position to have the corner thereof engaged by the pinching means.

7. Carton sealing means comprising means for pinching into parallelism the portions at the corner formed by two intersecting walls of a carton, driver means for passing a fastening means through said corner while it is so pinched, said last named means including a staple driver, said pinching means including an anvil element opposite the driver, and means for supporting a carton in position to have the corner thereof engaged by the pinching means.

8. A stapling machine for operating upon cartons, having a horizontal carton holding support, an overhanging arm above the support, and a stapling unit depending from the arm at an angle of 45° with a driver therein operating at an angle to drive the staple diagonally across the corner of a carton on the support, and anvil means set to operate against a side of the box through which the diagonally driven staple emerges, said anvil being associated with and forming part of a movable jaw element, and a second jaw element cooperating with the first for pinching the corner through which the staple is being driven.

9. A stapling machine comprising a pair of movable jaw elements adapted to pinch and grip the corner of a carton to be stapled, a driver positioned adjacent the jaw elements to drive a staple into the corner of the carton where it is so held and pinched, one of the jaw elements having an anvil portion toward which the driver projects the staple, and means for supporting the carton with the wall immediately under the driver initially in a plane at 45° to the direction in which the driver operates.

10. A stapling machine comprising a pair of movable jaw elements adapted to pinch and grip the corner of a carton to be stapled, a driver positioned adjacent the jaw elements to drive a staple into the corner of the carton where it is so held and pinched, one of the jaw elements having an anvil portion toward which the driver projects the staple, means for supporting the carton with the wall immediately under the driver initially in a plane at 45° to the direction in which the driver operates, and common means for operating the jaws and the driver in sequence.

11. The method of stapling a deformable but rigid carton which comprises pinching the corner formed by the intersection of two free edges of the carton until the parts so pinched are parallel and entering a fastening means through the parallel wall portions of the carton which are so pinched together.

12. A stapling machine comprising two opposed movable jaw members, a driver unit for

setting fastenings which unit is straddled by one of the jaw members and which terminates in spaced relation to the other of the jaws, and common means for operating the jaw members to pinch the corner of a carton to be fastened and for operating the driver to set a fastener in said corner.

13. Apparatus for stapling the corners of cartons comprising means for pinching the corner formed by perpendicular free meeting edges of the box to be stapled into parallelism, means for driving a staple through the portion which is so pinched, and means for moving and holding a box in position to be engaged by the pinching means with the diagonal line which extends from the corner of said box to the opposite corner being at right angles to the direction in which the driver moves.

JOSEPH C. LANG.
